DESIGN FOR A SHOE

Dominick J. Calderazzo, Brooklyn, N. Y., assignor to Dainty Maid Slippers, Inc., Brooklyn, N. Y., a corporation of New York

Application January 16, 1934, Serial No. 50,423

Term of patent 3½ years

To all whom it may concern:

Be it known that I, DOMINICK J. CALDERAZZO, a citizen of the United States of America, residing at 1245 Eighty-fourth Street, in the Borough of Brooklyn, county of Kings, and State of New York, have invented a new, original, and ornamental Design for a Shoe, of which the following is a specification, reference being had to the accompanying drawing, forming a part thereof.

Fig. 1 is a top plan view of the shoe showing my new design, and Fig. 2 is a side perspective view of the same.

I claim:

The ornamental design for a shoe substantially as shown.

DOMINICK J. CALDERAZZO.
